ABSTRACT OF THE DISCLOSURE

Low-foaming rinsing, washing and cleaning compositions comprising (A) from 90% to 99.9% by weight of at least one compound selected from the group consisting of anionic surface-active agents, amphoteric surface-active agents, non-ionic surface active agents, polymeric phosphates and complex-forming compounds, and (B) from 0.1% to 10% by weight of at least one foam inhibitor diurethane selected from the group consisting of diurethanes of the formula

and

wherein R represents a divalent hydrocarbon having from 2 to 20 carbon atoms and R₁ and R₂ represent monovalent hydrocarbons having from 8 to 30 carbon atoms.

THE PRIOR ART

It is known that non-ionic detergent substances, especially those based on polyglycol ethers, have a low-foaming power. The foam-inhibiting properties of these compounds, however, are often not sufficiently adequate to reduce the foam formation of such washing and cleaning agents which contain highly foaming tensides of the sulfate or sulfonate type. It has been, therefore, suggested to add fatty acids with more than 18 carbon atoms as foam inhibitors. The effect of these fatty acids is, however, limited to tensides of the sulfonate type and depends, in addition, upon the hardness of the water used for the preparation of the cleaning solution. The silicones widely used as foam inhibitors are less suitable for washing and cleansing agents since they may have a hydrophobizing effect on the cleaned objects and can be removed only with difficulty from the substrate.

Also in the use of tenside-free complexing polyphosphates or of tenside-free softeners containing organic complexing agents, which can be used for the removal of incrustations from textiles and washing machines, supply pipes and hot water heaters, considerable disturbances may occur through foam formation. Deposited organic impurities, such as proteins or fatty substances, lime soap residues or traces of detergents are held responsible for the foam formation.

OBJECTS OF THE INVENTION

An object of the present invention is to provide washing, rinsing and cleaning agents which, compared with the known agents, have an improved anti-foaming action independent of the nature and composition of the foaming compounds as well as of the hardness of the water, have no negative effect on the cleaning action of the

agents or on the usefulness of the cleaned substrate, are effective in small concentrations and overcome the disadvantages of the prior art.

Another object of the invention is to provide low-foaming rinsing, washing and cleaning compositions comprising (A) from 90% to 99.9% by weight of at least one compound selected from the group consisting of anionic surface-active agents, amphoteric surface-active agents, non-ionic surface active agents, polymeric phosphates and complex-forming compounds, and (B) from 0.1% to 10% by weight of at least one foam inhibitor diurethane selected from the group consisting of diurethanes of the formula

and

wherein R represents a divalent hydrocarbon having from 2 to 20 carbon atoms and R₁ and R₂ represent monovalent hydrocarbons having from 8 to 30 carbon atoms.

These and other objects of the invention will become more apparent as the description thereof proceeds.

DESCRIPTION OF THE INVENTION

The invention relates to low-foaming washing, cleaning and softening compositions with a content of at least one cleaning or complex-forming compounds from the class of anionic, amphoteric and non-ionic surface-active compounds, polymeric phosphates and complex-forming substances, characterized in that they contain 0.1 to 10% by weight, based on the quantity of the aforesaid cleaning and complex-forming compounds, of at least one foam-inhibiting diurethane of the following formulae:

and

wherein R represents a divalent hydrocarbon with from 2 to 20 carbon atoms, and R₁ and R₂ represent monovalent hydrocarbons with from 8 to 30 carbon atoms.

The hydrocarbons R, R₁ and R₂ may be straight or branched chain, saturated or unsaturated, or cycloaliphatic or aromatic. Compounds are preferably used in which R represents a divalent aliphatic hydrocarbon with from 2 to 10 carbon atoms, preferably alkylene and a divalent aromatic hydrocarbon having from 6 to 10 carbon atoms, preferably toluylene and phenylene, and the residues R₁ and R₂ represent monovalent straight-chain, saturated or mono-unsaturated hydrocarbons with 12 to 24 carbon atoms, preferably alkyl and alkenyl.

The foam-inhibiting alkylated alkylene or arylene diurethanes are obtainable in known way, for example diisocyanates of the formula

are reacted with primary or secondary alcohols, of the formulae R₁OH or R₂OH. In this case compounds of Formula I are obtained. Diurethanes of Formula II are obtainable by reacting dihydric alcohols or phenols with isocyanates of the formula R₁—N=C=O or

The alkyl residues R₁ and R₂ may be derived from fatty acids of natural or synthetic origin. Examples of these are octyl, decyl, lauryl, myristyl, cetyl, stearyl, arachyl, behenyl, lignoceryl, palmitoleyl and oleyl residues, and also their mixtures, such as, for example, are

present in coconut, tallow, rape oil, palm kernel oil, soya oil, cottonseed oil, tall oil, peanut oil or fish oil fatty acids or their hydrogenation products. The residues may also be derived from paraffin hydrocarbons, olefin polymers such as polyethylene, polypropylene and polybutylene, and compounds obtainable by ozon synthesis.

As has been shown, foam-inhibiting compounds in which the alkyl residues contain 10 to 14 carbon atoms, display their optimal action in the temperature range from 20° to 60° C. If the alkyl groups have 16 or more, especially 18 to 22 carbon atoms, the maximum foam-inhibiting action is displaced into the region from 60° to 100° C. By suitable choice or combination of foam inhibitors with different alkyl groups, therefore, the foaming behavior of the washing, cleaning and softening compositions can be controlled at will and adapted to the respective requirements.

Preferably, the washing, rinsing and cleaning compositions of the invention are low-foaming rinsing, washing and cleaning compositions comprising (A) from 90% to 99.9% by weight of at least one compound selected from the group consisting of anionic surface-active agents, amphoteric surface-active agents, non-ionic surface active agents, polymeric phosphates and complex-forming compounds, and (B) from 0.1% to 10% by weight of at least one foam inhibitor diurethane selected from the group consisting of diurethanes of the formula

and

wherein R represents a divalent hydrocarbon having from 2 to 20 carbon atoms and R₁ and R₂ represent monovalent hydrocarbons having from 8 to 30 carbon atoms.

The amounts of foam inhibitors to be used depend upon the amount of foaming or detergent substance present in the final composition and/or on the substrate to be cleaned as well as upon the magnitude of the desired effect. The practically important concentrations applied extend from 0.1% to 10%, preferably from 0.2% to 5% by weight, based on the solid composition. It is, of course, possible to work with still larger amounts, for instance, up to 25% by weight and more. This, however, is not required in the practice.

The foam inhibitors can be mixed with the other washing, cleansing and descaling agents in a conventional manner and can be processed together with them, for example, spray dried or granulated, or they can be converted by other known processes to solid, liquid or pasty mixtures. The foam inhibitors can also be mixed in molten or dissolved form with the other ingredients, present as powders or granules, or by sprayed or granulated on them. These other ingredients which are present in amounts from 90% to 99.9%, preferably 95% to 99.8% by weight, consist of at least one washing, bleaching, or complexing compound, such as anionic, non-ionic, amphoteric or cationic surface-active compounds, polymeric phosphates, complexing agents, as well as other non-surface-active builders, oxygen-containing bleaching agents and other ingredients customarily present in such agents.

The washing and cleansing agents can also contain anionic basic detergent substances of the sulfonate or sulfate type. Primarily alkylbenzene sulfonates, for example, dodecylbenzene sulfonate are suitable, also olefin sulfonates, such as, for example, are obtained by sulfonation of primary and secondary aliphatic monoolefins with gaseous sulfur trioxide and subsequent alkaline or acidic hydrolysis, as well as alkylsulfonates obtainable from n-alkanes by sulfochlorination or sulfoxidation and subsequent hydrolysis or neutralization, or by addition of bisulfite to olefins. Also suitable are α -sulfofatty acid esters, primary and secondary alkylsulfates and the sulfates of ethoxylated or propoxylated higher alcohols.

Other compounds of this class which can be optionally present in the washing composition are the higher molecular weight sulfated partial ethers and partial esters of polyhydric alcohols, such as the alkali metal salts of the monoalkylethers or mono fatty acid esters of the glycerine monosulfuric acid esters, or 1,2-dihydroxypropanesulfonic acid. Also sulfates of ethoxylated or propoxylated fatty amides and alkylphenols as well as fatty acid taurides and fatty acid isothionates are suitable.

Other appropriate anionic basic detergent ingredients are alkali metal soaps of natural or synthetic fatty acids, such as sodium soaps of coconut, palm kernel, or tallow fatty acids. As amphoteric detergent components, alkyl betaines and particularly alkyl sulfobetaines are suitable, for example, 3-(N,N-dimethyl - N - alkylammonium)-propane-1-sulfonate and 3-(N,N-dimethyl - N - alkylammonium)-2-hydroxypropane-1-sulfonate.

The anionic basic detergent ingredients can be present in the form of their alkali metal salts such as the sodium and potassium, and ammonium salt, as well as salts of organic bases, such as mono-, di- and triethanolamine. Inasmuch as the named anionic and amphoteric compounds have an aliphatic hydrocarbon radical, the latter should preferably be straight-chained and should have from 8 to 22 carbon atoms. In the compounds with araliphatic hydrocarbon radicals, such as alkylphenyl radicals, the preferred straight alkyl chains contain an average of from 6 to 16 carbon atoms.

As non-ionic surface-active basic detergent ingredients, primarily suitable are the polyglycoether derivatives of alcohols, fatty acids and alkylphenols which contain 3 to 30 glycol ether groups and 8 to 20 carbon atoms in the hydrocarbon radical. Particularly suitable are polyoxyethyleneglycoether derivatives in which the number of oxyethylene groups is 5 to 15 and whose hydrocarbon radicals are derived from straight-chain primary alcohols with 12 to 18 carbon atoms, or from alkylphenols with a straight-chain alkyl chain of 6 to 14 carbon atoms. By the addition of 3 to 15 mols of propylene oxide to the last named polyethyleneglycoethers, or by converting them into acetals, detergents are obtained which are distinguished by a special low foaming power.

Other suitable non-ionic basic detergent ingredients are the water-soluble polyethylene oxide adducts, containing 20 to 250 ethyleneglycoether groups and 10 to 100 propyleneglycoether groups adducted to polypropylene glycol, ethylenediamine-polypropyleneglycol and alkylene-polypropyleneglycol with 1 to 10 carbon atoms in the alkylene chain. The compounds utilized usually contain 1 to 5 oxyethylene units per oxypropylene unit. Also suitable as non-ionic compounds are those of the amine oxide and sulfoxide types, which, if necessary can be ethoxylated.

Preferred mixing constituents are also condensed phosphates, such as pyrophosphates, tripophosphates, tetraphosphates, trimetaphosphates and tetrametaphosphates in the form of the neutral or acid alkali metal salts, such as sodium or potassium salts. Preferably pentasodium tripophosphate and its mixtures with tetrasodium pyrophosphate are used.

The condensed phosphates may also be wholly or partly replaced by organic, complex-forming aminopolycarboxylic acids. These include especially the alkali metal salts of nitrilotriacetic acid and ethylenediaminetetraacetic acid. The salts of diethylenetriaminepentacetic acid and the higher homologs of the said aminopolycarboxylic acids are also suitable. These homologs may be prepared, for example, by polymerization of an ester, amide or nitrile of N-acetic acid aziridine and subsequent saponification to carboxylic acid salts or by reaction of polyalkylamines with a molecular weight of 500 to 100,000 with a haloacetic acid salt such as chloroacetic acid or bromoacetic acid salts in alkaline medium. Further suitable aminopolycarboxylic acids are poly-(N-succinic acid)-ethyleneimines and poly-(N-tricarballylic acid)-

ethyleneimines of average molecular weight 500 to 500,000, which are obtainable in a similar way to the N-acetic acid derivatives.

Further suitable builder salts are the complex-forming water-soluble potassium and, especially, sodium salts of higher molecular weight polycarboxylic acids, for example of polymerizes of olefinic unsaturated mono-, di- and tricarboxylic acids such as acrylic acid, maleic acid, fumaric acid, itaconic acid, citric acid, mesaconic acid, aconitic acid and methylenemalonic acid. Copolymerizes of these carboxylic acids with one another or with other copolymerizable substances are also useful, as for example, olefinic unsaturated hydrocarbons such as ethylene, propylene, isobutylene and styrene, with olefinic unsaturated monocarboxylic acids such as acrylic acid, methacrylic acid, crotonic acid and 3-butene carboxylic acid, or with other olefinic unsaturated alcohols, ethers, esters, amides and nitriles such as vinyl alcohol, allyl alcohol, vinylmethyl ether, acrolein, vinyl acetate, acrylamide and acrylonitrile. Copolymerizes from olefinic unsaturated mono-, di- and tri-carboxylic acids and several olefinic unsaturated compounds of different structure are also suitable. The polymerizes and copolymerizes have an average degree of polymerization of 3 to 6000 and, referred to 3 monomer units, should contain 1 to 9, preferably 2 to 9 carboxyl groups capable of forming salts.

The homopolymeric and copolymeric polycarboxylic acids capable of forming salts according to the foregoing definition can be represented by the following formula:

$R_1=H$ or CH_3 ,

$R_3=H$, CH_3 , phenyl, OH , CH_2OH , OCH_3 ,

CHO , $COOH$, $CONH_2$, CN ,

$X=H$ or $COOH$,

$Y=H$, $COOH$ or CH_2COOH ,

while X and Y do not both represent $COOH$ at the same time,

$Z=H$ or (provided $X=COOH$ and $Y=H$) also CH_3 ,

m =any numerical value from 0 to 2,

n =an integer between 3 and 6000.

The value of m is not restricted to whole numbers, but can take any optional numerical value, including also fractions of whole numbers from 0 to 2.

Further, complex-forming phosphorus-containing polycarboxylic acid salts may be present, for example the alkali metal salts of aminopolyposphonic acids, especially aminotri-(methylenephosphonic acid), ethylene-diaminotetra-(methylenephosphonic acid), 1-hydroxyethane-1,1-diphosphonic acid, methylenephosphonic acid, ethylenediphosphonic acid and also salts of the higher homologs of the said polyphosphonic acids. Mixtures of the aforesaid complex-forming substances are also useful.

Further builder salts are alkali metal silicates, especially sodium silicate, in which the ratio of Na_2O to SiO_2 amounts to 1:3.5 to 1:1. In addition, carbonates, bicarbonates and borates of alkali metals such as sodium or potassium, and acids, such as lactic acid and citric acid, may be added for adjustment of the pH value. The amount of the alkaline-reacting substances inclusive of the alkali metal silicates and phosphates should be such that the pH value of a liquor usable for coarse washing amounts to 9 to 12 and for fine washing 6 to 9. Compositions for mechanical dishwashing machines and for descaling of textiles, service pipes, washing machines and hot water heaters should be adjusted so that the liquor has a pH of from 9 to 14.

Further mixing components include oxygen-yielding

bleaching agents such as alkali metal perborates, percarbonates, perpyrophosphates and persilicates as well as urea perhydrate. It is preferred to use sodium perborate tetrahydrate. For stabilization of the per-compounds, the compositions may contain magnesium silicate, for example in amounts from 3 to 20% by weight, referred to the amount of perborate. Compositions to be used at temperatures below 70° C. for washing textiles, so-called cold washing compositions, may contain bleaching activators, especially tetraacetylglycoluril, as a powder component. The powder particles consisting of the bleaching activator or of the per-compound may be covered with coating substances, such as water-soluble polymers, fatty acids or salts granulated thereon, such as alkali metal silicates, sodium sulfate or disodium hydrogen phosphate, so as to avoid a reaction between the per-compound and the activator during storage.

Further suitable components of the mixtures are optical brighteners for cellulosic fibers, for example, those of the diaminostilbene-disulfonic acid type or its alkali metal salts according to the following formula

in which X and Y represent the following: $-\text{NH}_2$, $-\text{NH}-\text{CH}_3$, $-\text{NH}-\text{CH}_2-\text{CH}_2\text{OH}$,

$-\text{N}(\text{CH}_2-\text{CH}_2\text{OH})_2$, morpholino, dimethylmorpholino, $-\text{NH}-\text{C}_6\text{H}_5$, $-\text{NH}-\text{C}_6\text{H}_4-\text{SO}_3\text{H}$, $-\text{OCH}_3$, $-\text{Cl}$, where X and Y are the same or different. Compounds in which X represents an anilino and Y a diethanolamino or morpholino group are specially suitable.

In addition, optical brighteners of the diarylpyrazoline type according to the following formula may be present:

In the formula, Ar and Ar' represent aryl residues, such as phenyl, diphenyl or naphthyl, which may carry further substituents such as hydroxy, alkoxy, hydroxyalkyl, amino, alkylamino, acylamino, carboxyl, sulfonic acid and sulfonamide groups or halogen atoms. 1,3-diarylpyrazolines are preferably used in which Ar is p-sulfonamidophenyl and Ar' is p-chlorophenyl. In addition, whiteners suitable for the brightening of other types of fibers may be present, for example, such as of the type of naphthotriazolestilbene sulfonates, ethylene-bis-benzimidazoles, ethylene-bis-benzoxazoles, thiophene-bis-benzoxazoles, dialkylaminocoumarins, and cyanoanthracenes. These brighteners or their mixtures can be present in the washing composition in amounts from 0.01% to 1.5% by weight, preferably from 0.1% to 1% by weight.

Further suitable mixture ingredients are antigreying or 60 soil suspending compounds, such as sodium cellulose-glycolate, as well as the water-soluble alkali metal salts of synthetic polymers which contain free carboxylic groups. To them belong the polyesters or the polyamides of tri- and tetracarboxylic acids and dihydric alcohols or diamines, also polymeric acrylic, methacrylic, maleic, fumaric, itaconic, citraconic and aconitic acids, as well as the mixed polymerizes of the above-named unsaturated carboxylic acids or their mixed polymerizes with olefins.

Washing agents for washing textiles may also contain 65 restoring additives, for example, fatty acid amides of diamines or hydroxylalkyldiamines.

For a further improvement of the dirt loosening properties of the washing and cleaning compositions of the invention, they may also contain enzymes from the class 70 of the proteases, lipases and amylases, which may be

obtained from animal and vegetable origin, for example, from digestive ferments or yeasts, such as pepsin, pancreatic, trypsin, papain, catalase and diastase. Preferably, enzymic active substances are obtained from strains of bacteria or fungi, such as *Bacillus subtilis* and *Streptomyces griseus*, which substances are relatively stable towards alkalis, per-compounds and anionic detergent substances and are not appreciably inactivated even at temperatures between 45° C. and 70° C.

Further constituents which may be contained in the compositions according to the invention are neutral salts, especially sodium sulfate, bacteriostatic substances such as halogenated phenoethers and thioethers, halogenated carbanilides and acylanilides and halogenated diphenylmethanes, and dye-stuffs and perfumes.

The compositions according to the invention are marked by a high washing power. They are excellently suited for use in automatic drum washing machines, since they have no tendency to foam over even at temperatures above 90° C. or when the washing liquor is boiled.

Textile softener compositions according to the invention contain primarily alkali metal polyphosphates, such as sodium or potassium polyphosphates, for example, penta-sodium triphosphate, hexasodium tetraphosphate and their mixtures with polyphosphates of the formula $Na_{(n+2)}P_nO_{(3n+1)}$, where n represents a whole number from 5 to 20 and also sodium or potassium metaphosphates, such as sodium trimetaphosphate, sodium tetrametaphosphate, and sodium polymetaphosphates of the formula $(NaPO_3)_m$, where m represents a whole number from 5 to 30. The condensed phosphates may optionally be completely or partially replaced by complexing agents from the class of aminopolycarboxylic acids, alkanediphosphonic acids, hydroxyalkanediphosphonic acids, and aminoalkanopolyphosphonic acids, or their alkali metal salts.

The above-described washing, cleansing and softening compositions may optionally contain other known foam inhibitors, such as saturated fatty acids with 20 to 24 carbon atoms or their alkali metal salts, paraffins, higher molecular weight fatty acid esters or triglycerides, or trialkylmelamines. Such additions may often have a synergistic effect.

The qualitative and quantitative composition of the cleansing, bleaching or complexing ingredients, apart from the foaming inhibitors, is largely dependent upon the particular application of the composition and corresponds in the case of technically especially important washing and cleaning compositions to the following recipe (data in percent by weight):

1% to 40% of at least one compound from the class of the anionic, non-ionic and amphoteric surface-active compounds,

10% to 80% of at least one non-surface-active cleansing or complexing builder salt,

10% to 50% of a per-compound, especially sodium perborate, with or without crystalline water, as well as their mixtures with stabilizers and activators,

0.1% to 20% of other auxiliary and supplementary washing agent compounds.

The surface-active compounds can consist of up to 100%, preferably from 5% to 70%, of compounds of the sulfonate and/or sulfate type, up to 100%, preferably from 5% to 40% of non-ionic compounds of the polyglycoether type and up to 100%, preferably from 10% to 50%, of soaps. The builder salts can consist of up to 100%, preferably 25% to 95%, of alkali metal triphosphates and their mixtures with alkali metal pyrophosphates, up to 100%, preferably 5% to 50%, of an alkali metal salt of a complexing compound from the class of polyphosphonic acids, nitrilotriacetic acid, ethylenediaminetetraacetic acid and their alkali metal salts, and up to 100%, preferably from 5% to 75%, of at

least one compound of the class of alkali metal silicates, alkali metal carbonates and alkali metal borates.

To the additional auxiliary and supplementary washing agent compounds belong in addition to the optical brighteners, especially enzymes which can be present in an amount of up to 5%, preferably from 0.2% to 3%, and the additional anti-greying compounds which can be present in an amount of up to 5%, preferably from 0.2% to 3%.

The following specific embodiments are illustrative of the practice of the invention. They are not, however, to be deemed limitative in any respect.

EXAMPLES

A few compositions are given below which have proved especially good in practice. The invention is not restricted to the following mixtures, however, and these can be varied in many ways or be supplemented by the additional washing agent substances mentioned in the description.

The sulfate and sulfonate basic surface-active washing components and soaps are generally used as the sodium salts although other alkali metal salts may be employed. If liquid preparations are used, the anionic detergent substances may advantageously be used in the form of the mono-, di- or triethanolammonium salts.

(1) Pulverulent, weakly foaming washing agent

3% to 15% of sulfonate basic surface-active washing component from the class of alkylbenzene sulfonates, olefin sulfonates and n-alkanesulfonates,

0.5% to 5% of alkylpolyglycoethers (C_{12} to C_{18} -alkyl) or alkylphenolpolyglycoethers (C_8 to C_{14} -alkyl), with 5 to 10 ethyleneglycoether groups,

0 to 5% of soap (C_{12} to C_{18}),

0.2% to 5% of the anti-foaming agents of the invention as well as their mixtures with saturated fatty acids or their alkali metal soaps, containing 20 to 24 carbon atoms,

10% to 50% of a condensed alkali metal phosphate from the class of pyro- and triphosphates,

0.1% to 25% of sodium ethylenediaminetetraacetate or sodium nitrilotriacetate,

1% to 5% of sodium silicate,

10% to 35% of sodium perborate tetrahydrate,

0 to 5% of enzymes,

0.05% to 1% of at least one optical brightener from the class of the diaminostilbenedisulfonic acid derivatives or the diarylpyrazole derivatives,

0.1% to 30% of an inorganic salt from the class of the carbonates, bicarbonates, borates, sulfates and chlorides of alkali metals,

0 to 4% of magnesium silicate,

0.5% to 3% of sodium celluloseglycollate.

(2) Mechanical dishwashing agent

0.1% to 5% of compounds of the class of alkylpolyglycoether (C_{12} to C_{18} -alkyl) or alkylphenolpolyglycoether (C_8 to C_{14} -alkyl) with 5 to 30 ethyleneglycoether groups and 5 to 30 propyleneglycoether groups, and ethoxylated polypropyleneglycols,

0.1% to 5% of the anti-foaming agents of the invention,

45% to 90% of pentasodium triphosphate,

1% to 40% of sodium silicate ($Na_2O:SiO_2=1:1$ to $1:3$),

0 to 5% of potassium dichloroisocyanurate,

0 to 2% of other anti-foaming agents.

(3) Alkaline cleaning and bottle washing agent

0.1% to 5% of the anti-foaming agents of the invention,

0.5% to 50% of sodium silicate ($Na_2O:SiO_2=1:1$ to $1:3$),

0.5% to 80% of sodium hydroxide,

0 to 40% of trisodium phosphate,

0 to 40% of condensed alkali metal phosphates,

0 to 40% of sodium carbonate,

0 to 10% of hydroxyethane diphosphonate (sodium salt),
0 to 5% of anionic and/or non-ionic surface-active compounds.

(4) Softening agents

0.1% to 5% of anti-foaming agents of the invention,
20% to 95% of pentasodium triphosphate,
0 to 70% of a polyphosphate of the formula

$n=4$ to 20,

0 to 40% of sodium hexametaphosphate,
0 to 20% of sodium carbonate,
0 to 50% of sodium sulfate.

EXAMPLES 1 TO 26

The washing agents listed in Table II were used. The numerical data is in percent by weight. The sulfonate washing ingredients and the soaps were used as sodium salts. The α -sulfo fatty esters are methyl ester of a hydrogenated tallow fatty acid, sulfonated in the α -position to the ester group. The abbreviations are:

NTA=Sodium nitrilotriacetate

EDTA=Sodium ethylenediaminetetraacetate

CMC=Sodium salt of carboxymethylcellulose

EO=Ethylene oxide groups.

The difference to 100% by weight of the washing agents consisted in a mixture of the foam inhibitor and sodium sulfate, which was admixed to the washing agents as a dry powder. The composition and the percentage amount of the foam inhibitor, based on the total amount of washing agents can be found in Tables II and III.

The foaming behavior was tested in a commercial, fully automated washing machine with a horizontal drum while varying the washing liquor temperature as indicated. The machine was equipped with a round sight-window through which the foam level could be observed. The following notations were used for the evaluation of the foam height:

Maximum height of
the foam level

Notation:	40
0	No foam.
1	$\frac{1}{4}$ of the sight window.
2	$\frac{1}{2}$ of the sight window.
3	$\frac{3}{4}$ of the sight window.
4	$\frac{4}{4}$ of the sight window.
5	Foam visible in the filler tube.
6	Foaming over.

The washing machine was loaded with 3 kgm. of clean laundry. The concentration of the washing agent was 5 gm./liter. The weight ratio of textiles to washing liquor was 1:15. The hardness of the water was expressed in German degrees of hardness (1° dH corresponds to 1 mgm. CaO in 100 ml. water). The foam behavior is reported in Table III.

In the absence of a foam inhibitor, foaming over of the washing liquor occurred in all temperature ranges.

The foam inhibitors denoted below by S_1 to S_9 are tabulated in Table I. Types S_1 to S_5 are derived from diurethanes of Formula II, and types S_6 to S_9 are derived from those of Formula I.

TABLE I

Abbreviation: Foam inhibitor

S_1	Ethylene-di-(N-octadecyl-urethane).
S_2	Ethylene-di-(N-docosyl-urethane).
S_3	Hexamethylene-di-(N-octadecyl-urethane).
S_4	Hexamethylene-di-(N-tallow alkyl-urethane) (tallow alkyl=saturated C_{16} - C_{18} alkyl mixture).
S_5	Decamethylene-di-(N-octadecyl-urethane).
S_6	Hexamethylene-di-(O-dodecyl-urethane).
S_7	Hexamethylene-di-(O-octadecyl-urethane).
S_8	2,4-toluylene-di-(O-octadecyl-urethane).
S_9	2,4-toluylene-di-(O-dodecyl-urethane).

EXAMPLES 27 TO 31

In the following Table IV, examples for softening and descaling agents are given. The foaming inhibitors were admixed in solid form to the granular polyphosphate mixtures with the aid of an efficient pressure mixer. The agents are suitable for prewashing or descaling of textiles, as adducts to washing and dishwashing liquors in the use of hard water, and for the removal of lime sediments in washing machines and hot water heaters. Foaming of the treating solutions, whose concentrations varied from 0.5 to 5 gm./liter, was not observed.

TABLE IV

60	Examples	Amount in percent by weight					
			29	30	31	32	33
	Ingredient:						
	Compound S_7		0.3	0.5	0.3	0.8	0.5
	$Na_{(n+2)}P_nO_{3n+1}$:						
	With $n=3$		95.0	40.0	7.5	35.0	35.0
	With $n=4$ to 9		4.7	55.0	9.0	15.0	15.0
	With $n=10$ to 20		4.5	65.0			
	Sodium hexametaphosphate						30.5
	NTA						10.0
	Sodium silicate ($Na_2O:SiO_2=1:3.3$)						10.0
	Sodium carbonate						2.2
	Sodium sulfate						16.0
			29.2				4.0

The preceding specific embodiments are illustrative of the practice of the invention. It is to be understood, however, that other expedients known to those skilled in the art may be employed without departing from the spirit of the invention.

We claim:

1. Low-foaming rinsing, washing and cleaning compositions consisting essentially of (A) from 90% to 99.9% by weight of at least one compound selected from the group consisting of (1) anionic surface-active agents, (2) amphoteric surface-active agents, (3) nonionic surface-active agents, (4) alkali metal salts of polymeric phosphates selected from the group consisting of pyrophosphates, triphosphates, tetraphosphates, trimetaphosphates and tetrametaphosphates, (5) organic complex-forming compounds in the form of their alkali metal salts selected from the group consisting of aminopolycarboxylic acids, higher molecular weight polycarboxylic acids and amino-polysphonic acids, and (6) non-surface-active inorganic cleaner builder salts, and (B) from 0.1% to 10% by weight of at least one foam inhibitor diurethane selected from the group consisting of diurethanes of the formula

and

wherein R is selected from the group consisting of alkylene having from 2 to 10 carbon atoms and divalent aromatic hydrocarbons having from 6 to 10 carbon atoms, and R₁ and R₂ are selected from straight-chain monovalent hydrocarbons having from 12 to 24 carbon atoms selected from the group consisting of alkyl and alkenyl.

2. The low-foaming rinsing, washing and cleaning compositions of claim 1 wherein said foam inhibitor is present in an amount of from 0.2% to 5% by weight.

3. The low-foaming rinsing, washing and cleaning compositions of claim 1 wherein said ingredient A contains from 1% to 40% by weight of said ingredient A of at least one surface-active compound selected from (1) anionic surface-active agents, (2) amphoteric surface-active agents and (3) non-ionic surface-active agents, from 1% to 80% by weight of said ingredient A of at least one of components (4), (5) and (6), from 10% to 50% by weight of said ingredient A of an active-oxygen per-compound, and from 0.1% to 20% by weight of said ingredient A of auxiliary and supplementary washing agent compounds selected from the group consisting of from 0.2% to 3% by weight of said ingredient A of enzymes selected from the group consisting of proteases, lipases and amylases, from 0.2% to 3% by weight of said ingredient A of greying inhibitors, from 0.01% to 1.5% by weight of said ingredient A of optical brighteners and from 0 to 5% by weight of said ingredient A of foam inhibitors selected from the group consisting of saturated fatty acids

having 20 to 24 carbon atoms and their alkali metal salts, paraffins, triglycerides of fatty acids and trialkylamines.

4. The low-foaming rinsing, washing and cleaning compositions of claim 1 wherein said ingredient A consists of components (4) and (5) selected from the group consisting of polyphosphates of the formula

and metaphosphates of the formula

wherein Me represents a metal ion selected from the group consisting of sodium and potassium, n represents an integer from 3 to 20 and m represents an integer from 5 to 30, sodium nitrilotriacetate, potassium nitrilotriacetate, sodium ethylenediaminetetraacetate and potassium ethylenediaminetetraacetate.

5. The low-foaming rinsing, washing and cleaning composition of claim 3 wherein said active-oxygen per-compound is selected from the group consisting of anhydrous sodium perborate, sodium perborate containing water of crystallization, and their mixtures with per-compound stabilizers and activators.

6. The low-foaming rinsing, washing and cleaning compositions of claim 3 wherein said at least one surface-active compound consists of from 25% to 70% by weight of surface-active sulfonates and sulfates, from 5% to 40% of non-ionic polyglycoethers and from 10% to 50% of soap.

7. The low-foaming rinsing, washing and cleaning compositions of claim 3 wherein said components (4), (5) and (6) consist of from 25% to 95% of alkali metal triphosphates and their mixtures with alkali metal pyrophosphates, from 5% to 50% of an alkali metal salt of a complexing compound selected from the group consisting of polyphosphonic acids, nitrotriacetic acid and ethylenediaminetetraacetic acid, and from 5% to 75% of at least one compound selected from the group consisting of alkali metal silicates, alkali metal carbonates and alkali metal borates.
